UNITED STATES PATENT OFFICE.

JOSEPH E. MCGINNESS, OF PITTSBURGH, PENNSYLVANIA.

GOLF-BALL MARKER.

Application filed April 29, 1927. Serial No. 187,520.

My invention consists of an improvement in golf ball markers. It has for its object to provide means for clamping the ball between opposed opening and closing rotatable holders, for positive pressing and feeding action against a slidably mounted row of printing or stamping type.

The device is provided with means for rotating the ball between its holders, means for adjusting the holders to close clamping or open relieving position simultaneously, means for rotating the ball by actuating one of said holders to roll the ball over imprinting type, an improved type carriage, and various other features of construction and advantage, as hereinafter more fully described.

Referring to the drawings, showing one preferred form of the invention:

20 Fig. 1 is a plan view of the golf ball marker in closed operative position;

Fig. 2 is a view of the machine in side elevation, the turning handle having been removed;

25 Fig. 3 is a plan view, with the ball holding frame thrown over to open position;

Fig. 4 is a view of the machine in end elevation on the right hand side of Fig. 2;

30 Fig. 5 is a cross-section on the line V—V of Fig. 2, with the ball holding clamps receded;

Fig. 6 is a longitudinal vertical sectional view on the line VI—VI of Fig. 1, with the clamping frame of the ball holder thrown 35 upwardly to open position;

Fig. 7 is a developed diagrammatic view of the opening and closing cams.

The machine as a whole consists of a supporting frame 2, provided with downwardly 40 extending pedestals 3 at each end, sufficiently broad to support the frame on a table top or other surface, without tilting.

Frame 2 is of open skeleton construction for lightness, having at one end a projecting 45 grasping tang or handle 4, while trackways 5 for the type carriage 6 extend along the middle inner side portions of the frame, for slidable movement thereon of the carriage. Near the other end, beyond the middle operative portion of the machine, supporting arms 7 extend upwardly at each side, providing a mounting for the cross bar or rod 8, upon which is hinged the ball holder.

Said holder is of composite construction, 55 comprising a main rectangular open frame 9, having hinge lugs 10 for connection with

the hinge rod 8, and provided at the other end with a grasping and holding handle 11.

A pair of transverse guiding and supporting slide rods 12 extend across the frame 9, 60 within its outer edge portions, and are mounted in bearings 13 of the ends 14 of the frame.

Slidably mounted on rods 12 are the cross arms or spiders 15 adapted to be moved 65 outwardly and inwardly from and towards each other simultaneously, by means of the surrounding cam shells 16. These are provided with oppositely located cam grooves 17, adapted to engage the terminal pins or 70 abutments 18 of frames 15 above and below, as the cams are rotated around a central transverse axis.

Such axis is provided by stems 19 and 20, 75 in axial alignment and connected with the inner ball clamps 21 and 22 respectively. Each is provided with an inner circular cavity and an inserted gripping open-center ring 23 of rubber or other suitable material adapted when brought together to clamp 80 the opposite side portions of the golf ball A, as in Fig. 4.

The cams 16 are provided with end walls 24 which are journalled around the stems 19 and 20 for rotation thereon, and the cams 85 are also connected by a rigid integral cross-piece 25 having an operating handle 26.

As thus constructed it will be seen that the cams may be rotated together to open the ball clamps when handle 26 is thrust upwardly as in Fig. 6, and to bring the ball gripping members 21 and 22 together around the ball, when the handle 26 is lowered, as in Fig. 2.

When the ball is thus gripped, it may be 95 rotated by a handle 27 of stem 19, whereby both gripping heads and the ball will be rotated to feed the surface of the ball over the face of the type of the carriage, as it is moved from one end to the other by such 100 rotating contact. Stems 19 and 20 are rotatably mounted in bearings 28 of the cross bars 14 of main frame 9.

A tubular shell 29 is secured around stems 19 and 20 and is slidably and rotatably mounted within bearings 28. Shell 29 bears against the outer side of each spider frame 15, so that the spider frame thus bears positively against the inner end of the sleeve at one side and the hub of the ball clamp at the 110 other, for positive movement in either direction.

The type carriage 6 consists of a rectangular double sided casing adapted to slide over the tracks 5 under engagement of the ball. The carriage is provided with a middle type holding box or case 30 in which are mounted the printing type 31, held therein by terminal and side set screws 32.

For the purpose of inking the type for action against the surface of the ball A as it is rotated over the printing terminals of the type, I provide an inking ribbon 33 extending around cross guide pins 34 from winding and unwinding rollers 35, 36 respectively, at opposite ends of the frame 6.

15 One such roller may be wound from time to time for drawing a new section of ribbon over the type from the other roller, by turning the supporting pin by its terminal 37, as will be readily understood.

20 The ribbon winding and unwinding stems are mounted across between extended wings 38 of the carriage at each side of each end, beyond the type holding body. Said wings fit down between the tracks 5 as in Fig. 5 25 for proper guiding engagement, while the type carriage as a whole is supported on the tracks by lugs 39.

As shown, the top side edges 40 of the type carriage extend upwardly forming outer parallel tapered bearing edges for the ball, substantially on the same level as the top of the type. The ribbon lies over the type between said edges, passing down between their ends to the cross holding pins 37. As 30 the ball is rotated over the top of the carriage it will contact with the edges 40 with sufficient friction to move the carriage until the ball engages the type. Due to the curved contour of the ball, it will then ride upwardly slightly and onto the type, away from the edges 40 just sufficient for clearance, with ample pressure for good marking.

Beyond the type the ball will again ride 45 onto the edges, so that good marking impression is ensured without danger of distortion or cutting of the ball surface.

The general construction and operation of the machine will be readily understood and appreciated from the foregoing description.

50 By merely throwing up the handle 26 the cams 16 will thrust the ball holders to their open position ready to receive the ball A between them, and upon reversing the handle 26 the ball will be tightly clamped therebetween. The cam groove 17, as shown in Fig. 7, is provided with a comparatively straight terminal portion 17^a, ensuring tight holding engagement with the pins 18 and avoiding looseness or slippage.

The ball being thus clamped it is rotated by handle 27 across the surface of the printing type, such movement automatically shifting the carriage along its trackway for the desired distance. Thereafter the frame may

be thrown upwardly, the ball clamps separated and the ball removed, and the operation repeated as desired.

Due to the construction and arrangement 70 the machine admits of a certain variation in diameter of ball, and the holding frame may be lowered until the surface of the ball comes into contact with the type, when it is ready for operation.

The entire machine is comparatively simple in construction, cheap, and easily manipulated, and is continuously serviceable, without getting out of order.

It may be changed or varied in different 75 details or design, but all such changes are to be considered as within the scope of the following claims.

What I claim is:

1. A golf ball marker comprising a supporting frame having a freely movable type 80 carriage, an upper ball holder having inwardly and outwardly movable cam actuated open ring ball clamps, and means for rotating the ball clamps.

2. A golf ball marker comprising a supporting frame having a freely movable type carriage, a ball holding frame hinged above the carriage, laterally movable open ring ball clamps on said frame, and means embodying double-acting cams for opening 95 and closing the clamps together.

3. A golf ball marker comprising a supporting frame having a freely movable type carriage, a ball holding frame hinged above the carriage, laterally movable ball clamps on said frame, and double-acting cam actuated mechanism for opening and closing the clamps together.

4. A golf ball marker comprising a supporting frame having a freely movable type carriage, a ball holding frame pivotally supported above the carriage and provided with a pair of opening and closing rotatable ball clamps, a rotating stem and handle for one of said clamps, and a separately acting lever mechanism for actuating the clamps mounted on the ball holding frame.

5. In combination, a supporting frame having a middle longitudinal trackway for a printing carriage, a longitudinally movable carriage thereon having upwardly extending type, an open ball supporting frame pivoted above the trackway and having a handle, a pair of rotatable ball clamps slidably mounted on said frame, a rotating handle for one of said clamps, and cam mechanism for moving the clamps inwardly and outwardly together.

6. In combination, a supporting frame having a middle longitudinal trackway for a printing carriage, a longitudinally movable carriage thereon having upwardly extending type, an open ball supporting frame pivoted above the trackway and having a handle, transverse slide rods thereon, spider 125

frames slidably mounted on the cross arms having middle spindle bearings and cam engaging lugs, a pair of ball clamps having spindles rotatably mounted in the middle bearings, and cams rotatably mounted on the spindles having cam grooves engaging the lugs.

7. In combination, a supporting frame having a middle longitudinal trackway for a printing carriage, a longitudinally movable carriage thereon having upwardly extending type, an open ball supporting frame pivoted above the trackway and having a handle, transverse slide rods thereon, spider frames slidably mounted on the cross arms having middle spindle bearings and cam engaging lugs, a pair of ball clamps having spindles rotatably mounted in the middle bearings, and a pair of cams rotatably mounted on the spindles having cam grooves engaging the lugs and provided with a connecting handle arranged to be opened and closed from and towards the handle of the supporting frame.

25. 8. The combination with a longitudinal lower trackway, and an upper ball holding

frame having means for clamping and rotating a ball, of a carriage slidably mounted in the trackway having upper bearing edges for a ball, a row of type between the bearing edges and a printing ribbon laid over the type between said edges.

9. The combination with a longitudinal lower trackway, and an upper ball holding frame having means for clamping and rotating a ball, of a carriage slidably mounted in the trackway having a middle type holding cavity, side ball supporting edges, and a printing ribbon laid along between the edges and provided with winding and unwinding stems at the ends of the carriage.

10. A type holding carriage for a golf ball marker consisting of a type holding box having upper longitudinal ball bearing edges, side supporting lugs, side frame-bearing cheeks at each end, and cross pins between the cheeks, with a printing ribbon passing over said pins and lying between the ball bearing edges.

In testimony whereof I hereunto affix my signature.

JOSEPH E. McGINNESS.
